United States Patent Office

Des. 221,274
Patented July 27, 1971

221,274

LUGGAGE LATCH

William J. Bouton, Jr., South Norwalk, Conn., assignor to
The Excelsior Hardware Company, Stamford, Conn.

Filed May 5, 1970, Ser. No. 22,823

Term of patent 14 years

Int. Cl. D8—03

U.S. Cl. D8—122

FIG. 1 is a top perspective view of a luggage latch showing my new design;

FIG. 2 is a top view of said luggage latch;

FIG. 3 is a side view of said luggage latch;

FIG. 4 is an end view looking onto the left end of FIG. 3; and

FIG. 5 is an end view of said luggage latch looking onto the right end of FIG. 3.

I claim:

The ornamental design for a luggage latch, as shown.
